(57) **CLAIM**

We claim the ornamental design for a cutting tool, as shown and described.

DESCRIPTION

FIG. 1 is a top, front, left side perspective view of a cutting tool.

FIG. 2 is a front elevation view of the cutting tool of FIG. 1, the rear elevation view being identical.

FIG. 3 is a right side elevation view of the cutting tool of FIG. 1, the left side elevation view being identical.

FIG. 4 is a top plan view of the cutting tool of FIG. 1; and, FIG. 5 is a bottom plan view of the cutting tool of FIG. 1.
